GAME AND APPARATUS THEREFOR

James Y. Morris, Lexington, N. C.

Application April 12, 1938, Serial No. 201,478

1 Claim. (Cl. 273—104)

This invention relates to a game and apparatus therefor, the game being one of exercise, amusement and skill.

It is an object of the invention to provide an apparatus for playing a game wherein two similar goal posts are employed, each having a counting mechanism associated therewith so that the scores of each player or set of players are kept by the opposing side, and wherein suitable perforated members are used for pitching, each post having upwardly extending pins around which players endeavor to pitch the perforated members.

In the drawing forming a part thereof:

16 Figure 1 is a perspective view of a pair of spaced goal posts showing a player pitching rings at a distant post;

Figure 2 is an enlarged view of the scoring apparatus associated with each goal post.

20 Each goal post comprises a pair of base members 10 and 11, having a cross-piece 12 secured to the top thereof with king pins or goal posts 13 and 14 projecting upwardly from the ends of cross-piece 12. The base members 10 and 11 have notches in their upper edges and the cross-piece 12 fits snugly in the notches. A hole is bored through each end of cross-piece 12 and extends into the base piece. The pins 13 and 14 are then driven to the position shown in dotted lines and this serves to hold the base pieces and the cross-piece together. Secured to an intermediate portion of cross-piece 12 is an upright 15 having another cross-piece 16 thereon in which the lower ends of U-shaped wire member 17 are secured.

35 Slidably mounted on this wire member is a plurality of chips 18, there being the same number of chips on each goal post. The goal posts are indicated broadly by reference characters A and B, but like reference characters apply to the structure of both posts. As an adjunct to the game and forming a part of the apparatus I provide a plurality of rings 20 and 21. If desired these rings may have one or more projections 22 thereon to prevent the same from rolling any great 40 distance if they fail to become lodged on the goal pin. These rings may be made of any suitable material, such as metal, rubber or composition material.

45 Suppose two persons are playing the game. 50 One person will stand at goal post B as shown in the drawing, and another person will stand at goal post A. They would each have two rings 20 and 21. The player at post A keeps the score of the player at post B and conversely, the player

at B will keep the score of the player at A. In the drawing the man at B goal post is shown pitching the ring at his goal post A which is supervised by his rival player. It is seen that the player at goal post B has already tossed one ring over the pin 13, counting one point. If he tosses the next ring which is shown in the air, and it also becomes lodged on goal post 13, he gets the second point plus an extra point for placing two rings in succession over the pin 13. 5 10 This would mean that the opponent at goal post A would pick up three of the chips from one side of the U-shaped member and slide them over to where they would be disposed on the other side of the U-shaped member. In turn, the player 15 at goal post A would toss a ring with a view to encircling one of the pins 13 of goal post B. His score would be kept by his opponent by the counting mechanism at the top of goal post B. In starting the game, of course, all the chips would 20 be stacked on one side of the U-shaped member at each goal post, and whichever player succeeding in winning enough points to cause all of his chips to be moved over to the other side of the U-shaped member would be the winner of the 25 game.

30 Rules for four players would be the same, except that partners would play the same goal posts.

In the drawing and specification, there has been set forth a preferred embodiment of the 30 invention, and although specific terms are employed, they are used in a generic and descriptive sense only and not for purposes of limitation, the scope of the invention being set forth in the appended claim.

35 I claim:

A knockdown game apparatus comprising a pair of spaced semi-circular base members each having a lower flat edge adapted to rest on the ground, the uppermost portions of the base members each having a transversely disposed notch therein, a cross member having its ends fitting in said notches, the ends of the cross member and the base members having coinciding holes penetrating the cross members and extending from 40 the bases of said notches downwardly into the base members, and a goal post having its lower end snugly penetrating the holes in the ends of the cross member and snugly fitting into the holes in the base members to secure the cross 45 member and the base members together, said goal pins projecting upwardly above the cross member to serve as goal posts for the apparatus.

JAMES Y. MORRIS.
